IGNITER.

1,307,342.

Specification of Letters Patent. Patented June 24, 1919.

Application filed October 2, 1918. Serial No. 256,615.

To all whom it may concern:

Be it known that I, PHELPS BROWN, a citizen of the United States of America, residing at Springfield, in the county of 5 Hampden and State of Massachusetts, have invented certain new and useful Improvements in Igniters, of which the following is a specification.

This invention relates to igniters and 10 more particularly to igniters of the reciprocatory armature type.

Igniters of this general type possess many important and now well recognized advantages, but heretofore their field of 15 service has been somewhat restricted by reason of their noisiness in operation. According to one example of prior practice, the igniter is so constructed that flux from a source of magnetism may be first directed 20 through the cores of a generating winding and then shunted or excluded from said cores. Heretofore, two armatures, each reciprocable to and from the cores, have been provided for this purpose and one armature, 25 by engagement with the cores at one end, is arranged to complete a magnetic circuit therethrough from the source of magnetism, while the other armature, by engagement with the cores at the other end, shunts the 30 flux and excludes it from the cores. The armatures are also commonly moved at very high speed in one direction and it follows that that armature, which engages the cores on the high speed stroke, must necessarily 35 be arrested very suddenly and the impingement of such armature with the cores produces a great deal of noise. This invention is concerned, among other things, with the elimination of one armature, (the one which 40 is notoriously noisy in operation) and, by such elimination, not only is the operation of the igniter made more quiet, but a very substantial reduction in the weight of the moving parts is accomplished, as well as 45 other advantages as will later appear.

The invention has for its object to provide an igniter, wherein an armature is provided to coöperate with the core of a generating coil and by movement to and from such 50 core, to establish and interrupt a magnetic circuit from a suitable source of magnetism through such core, together with means including a permanent air gap to provide a shunt path for the flux from said source 55 when the armature is moved away from the core.

According to this feature of the invention, a permanent shunt path is provided across the poles of the source of magnetic flux, but such path by reason of the permanent air gap is of higher reluctance than the magnetic path through the core and armature, when these latter elements are in engagement, and of less reluctance than the latter path, when the last-named elements 60 are separated by an air gap. Thus, with the armature in engagement with the core, the major portion of the flux is directed through the latter while, when the armature is separated from the core, the major portion of 70 the flux traverses the permanent shunt path, and the permanent air gap therein, to assist in the diversion of the flux from the core.

Other objects and advantages will appear in the following description and in the illustrative embodiment of the invention in the accompanying drawings, in which:

Figure 1 is a top plan view of an igniter embodying the invention;

Fig. 2 is an elevational view thereof with 80 certain parts broken away;

Fig. 3 is a cross-sectional view taken on the line 3—3 of Fig. 1; and

Fig. 4 is a diagrammatical view illustrative of the electrical connections of the ig- 85 niter.

Referring to these drawings: The igniter includes essentially a suitable source of magnetic flux, as a permanent magnet 6; a suitable generating winding, as the coil 7; a core, as 8, with which an armature, as 9, co-operates to alternately establish and interrupt a magnetic circuit from the source 6 through the core 8 and generating winding 7; and means providing a shunt path across 90 the poles of the magnetic source, as the magnetic conductors 10 and 11, which are separated by a permanent and relatively small air gap 12.

The essential elements of the invention, as 100 thus briefly described, may be varied in many particulars and still embody the invention and the following specific description of these essential elements is to be taken as merely illustrative. In addition to the 105 elements described there may be, and preferably are, provided other elements, as will appear, to the end that the igniter may be made more efficient for its intended use. The following description is, therefore, to 110 be considered merely as an illustrative example of one suitable form of igniter, in

which the invention may be embodied, and it is recognized that the illustrated structure may be varied in numerous ways and still embody the invention.

- 5 In the brief general description, the armature 9 was said to coöperate with the core 8 to alternately establish and interrupt a magnetic circuit from the magnetic source 6. This coöperation of elements to accomplish 10 the stated function does, in the illustrated embodiment of the invention, make use of an intermediary element 13 between the source 6 and armature. Such intermediary element is not necessarily essential for all purposes, but is generally to be preferred and is here provided in the shape of a second core 15 on which a second generating coil 14 may be mounted to increase the efficiency of the igniter.

20 Each core may advantageously be combined with the adjacent magnetic conductor, already described as forming an element of the shunt path. Thus, the members 8 and 10 may be made up in one elbow shaped 25 unit, as shown, and the members 11 and 13 may be made up in a similar manner. Preferably, as indicated in Fig. 1, the elements 8, 10, 11 and 13 are built up of a plurality of soft iron laminations in the usual 30 and well known manner.

25 The source of magnetic flux may advantageously consist of one or more permanent bar magnets 6. As shown, two magnets 6 are provided; one on each side of the cores, 35 although obviously a greater or less number of magnets may be used, as desired. One pole of each magnet, as the north magnetic pole, is magnetically connected to the core 8 and to the shunt forming extension 10 and 40 the other pole of each is magnetically connected to the core 13 and to the shunt forming extension 11. This connection of the magnets, cores and extensions may be accomplished in any suitable manner. For 45 example, two angle shaped blocks 15 may be provided, as shown in Fig. 1, to partially encompass the laminations of the combined members 8 and 10 and a like arrangement may be provided for the combined members 50 11 and 13. The magnets 6 then bridge across and connect each pair of blocks 15 and the entire assembly described may be held together by suitable means, as retaining bolts 16.

55 To mechanically, but not magnetically, connect the lower ends of cores 8 and 13, two cross-bars 17 of non-magnetic material are provided and such cross-bars may be mounted on and secured to the cores in a manner 60 similar to that in which the magnets 6 are mounted and secured. The bars 17, and thus the entire assembly described, are supported from a suitable frame A through the intermediary of a pair of brackets 18 and a plate 65 19. The latter is offset downwardly inter-

The spring 20 constitutes the means for 70 moving armature 9 toward the cores 8 and 13. Any suitable means may be provided to disengage the armature 9 from the cores and move it in the opposite direction. For example, a bar 21, having a forked lower 75 end to straddle armature 9, is slidably mounted in and between the cross-bars 17. A spring 22, interposed between the upper end of bar 21 and a block 23, of non-magnetic material held between the magnets 6, 80 tends to move bar 21 downwardly. The bar 21 may be raised by a cam 24 fixed on a shaft 25 rotatably mounted in casing A. Shaft 25 may be driven at any desired speed in the illustrated direction by means with 85 which the present invention is not concerned. As shown in Fig. 3, the extreme lower end of bar 21 rides upon the periphery of cam 24 and therefore will be gradually raised thereby, thus allowing the 90 armature 9 to be moved upwardly into engagement with the cores 8 and 13 under the force of spring 20. The cam 24 is preferably arranged to lift bar 21 a farther distance to 95 permit the separation of its armature engaging portion from the armature, thus compressing spring 22. Cam 24 is also so constructed as to periodically allow bar 21 to drop and be suddenly moved downwardly under its weight and the force of spring 22 100 to forcibly dislodge the armature 9 from the cores 8 and 13, to which it is, of course, magnetically held. The downward movement of bar 21 is sufficient to separate the armature 9 from the cores 8 and 13 by an 105 air gap greater than the air gap 12 existing between the adjacent ends of the shunt forming extensions 10 and 11.

If desired, in addition to the main or primary generating winding (comprising 110 the coils 7 and 14), there may be provided a secondary winding comprising coils 26 and 27 superimposed upon the coils 7 and 14 respectively. If secondary coils are used, the primary winding should, as shown in Fig. 4, 115 be arranged in a closed circuit which should be interrupted periodically to induce an electro-motive force in the secondary winding. Thus, the primary coils 7 and 14, which are suitably connected together (as in series by 120 the wire 28), have their terminal wires 29 and 30 electrically connected to the breaker points 31 and 32, respectively, of an interrupter. Preferably, as is usual, a condenser 33 is bridged across the breaker points 31 125 and 32. The secondary coils are also suitably connected together (as in series by a wire 34), and the terminals of the secondary winding are represented by 35 and 36 one (as 36) being preferably grounded to conform to 130

the general practice. As shown in Fig. 2, one breaker point, as 32, is adjustably secured to and insulated from base A and the other breaker point, as 31, is carried on the 5 end of one arm of a bell crank lever 38 pivoted at 39 to frame A. A suitable spring 40 tends to hold the breaker points 31 and 32 in contact and they are automatically separable during the downward flight of 10 armature 9, by the engagement of the other arm of the lever 38 with a projection 42 (Fig. 3) on armature 9.

In operation, as shaft 25 revolves, cam 24 periodically raises bar 21, as described, and 15 thus allows the armature 9 to be moved upwardly into engagement with the lower ends of cores 8 and 13. The armature, at such time, magnetically connects the core ends and a magnetic circuit from the magnets 6 through both cores and the armature results. This circuit is obviously of lower reluctance 20 than the shunt circuit for the magnets, which shunt circuit includes the extensions 10 and 11 and the permanent air gap 12. Therefore, the major portion of the flux 25 from magnets 6 will encircle the primary generating winding. It has been described that the cam 24 subsequently releases bar 21 and allows it to be rapidly moved downwardly to forcibly dislodge the armature 9 from the core ends and thereby interrupt 30 the magnetic circuit theretofore existing through the cores. As is well known, upon interruption of a magnetic circuit, there is 35 not the immediate cessation of flux in the circuit that might be desired in order to produce the maximum change of flux in the generating windings, and thus the generation of the maximum electro-motive force 40 therein. The lines of force tend to jump the air gap and it is known that such tendency results in a rapid weakening of the magnets. It is to prevent such rapid deterioration 45 of the magnets and also to divert the flux as soon as possible from the cores, that the shunt path is provided for the magnets during that period when the armature is separated from the cores.

This shunting of the flux is, according to 50 this invention, accomplished by means which include a permanent air gap, as 12, as distinguished from a movable magnetic member which periodically bridges the poles of the magnets and shunts the flux therefrom. Thus, as soon as the armature 9 has 55 been separated from the core ends a distance equal to half the length of air gap 12, the reluctance of the shunt path (including parts 10, 11, and 12) is at least no greater than 60 that of the path which includes the cores 8 and 14, the armature 9, and the double air gap between the armature and cores. As the armature 9 continues to move farther away 65 from the core ends, the reluctance of the

winding increases very rapidly and the major portion of the flux then traverses the shunt path and is diverted from the cores. Practically, since armature 9 in its downward flight moves at high speed, there is produced a rapid change of flux in cores 8 and 14 and thus a current is generated in the primary winding. 70

If the secondary winding is used, (and it may be used to advantage although not 75 necessary to the invention) the current generated in the primary winding flows in a closed path, as described, and, substantially at the time when maximum current exists in the primary winding, the breaker points 31 and 32 are separated by the downward flight 80 of armature 9, whereby the normally closed circuit is interrupted and an electro-motive force is induced in the secondary winding. 85

The invention is particularly characterized by the provision of means affording, for the magnetic source, a shunt path of substantially constant reluctance and of a reluctance greater than that of the magnetic circuit through the generating winding, 90 when the armature engages the cores, and less than that of the last-named magnetic circuit, when the armature is moved away from the cores. By this means, a diversion 95 of the flux from the generating windings is obtained upon interruption of the magnetic circuit theretofore encircling such windings. Moreover, and this is most important, I obtain this desirable result without requiring a movable magnetic member, as a second 100 armature, which engages and connects the upper ends of the cores at substantially the time that the armature 9 is disengaged from the lower ends of the cores. The elimination 105 of such second armature results in the elimination of much of the noise in operation which has heretofore characterized igniters of this type for, obviously, the impingement of a fast traveling metallic member on stationary metallic members contributes largely to the production of noise, 110 much more so indeed than the impingement of bar 21 on armature 9, for the latter is yieldably supported and cushioned against the blow. Moreover, the armature engaging 115 portion of bar 21 need not be metallic.

The elimination of the second armature also results in a marked reduction in the weight of moving parts, which is important not only as to economy of material, but more 120 particularly as to its effect on high speed operation. Large and relatively heavy moving bodies necessarily interfere by reason of their weight and inertia with the desired high speed operation. 125

Certain features of this invention are shown but not claimed in a copending application Serial No. 259,530, filed October 24, 1918.

The invention has been disclosed herein 130

in a single form for illustrative purposes, but many other forms and arrangements will readily suggest themselves to those skilled in the art, having for their object the use of the invention in a specific form differing from the one disclosed. It is, therefore, desired to have the scope of the invention determined by the appended claims interpreted in the spirit of the disclosure rather than in the letter of the exact form disclosed.

What I claim is—

1. In an igniter, a source of magnetic flux, means including coöperating and relatively movable members to provide a magnetic circuit of varying reluctance from said source, a generating winding associated with one of said members, and means at all times providing a second magnetic path of constant reluctance for the flux from said source, the reluctance of the second path being greater than the minimum and less than the maximum reluctance of said circuit.
2. An igniter, comprising, a source of magnetic flux, means including a core and coöperating armature to provide a magnetic circuit from said source, a generating winding associated with said core, means to move the armature away from said core to de-

crease the flux through the core and winding, and means at all times providing a shunt path for the flux from said source, said means including a relatively small permanent air gap and affording a shunt path of constant reluctance.

3. An igniter, comprising, a source of magnetic flux, a generating winding, a core for the latter having one end magnetically connected to one magnetic pole of said source, an armature movable toward and away from said core to magnetically connect and disconnect the latter to and from the other magnetic pole of said source, and means permanently and magnetically connecting the poles of said source except for an air gap of less length than the maximum air gap between said core and armature.

4. In an igniter, two magnetic conductors separated at one end by a relatively small air gap and at the other end by a relatively large distance, an armature to alternately connect and disconnect the last-named ends of said conductors, a source of magnetic flux connecting said conductors intermediate their ends, and generating coils on said conductors between said source and the last-named ends of the conductors.

PHELPS BROWN.
